UNITED STATES PATENT OFFICE

RUDOLPH F. MALLINA, OF ATLANTIC CITY, NEW JERSEY, ASSIGNOR TO VICTOR TALK-
ING MACHINE COMPANY, A CORPORATION OF NEW JERSEY

MEMBER OR STRUCTURE VIBRATED BY ENERGY IMPULSES

Application filed October 10, 1928. Serial No. 311,487.

My invention relates to a member or structure partaking of vibratory motion under the influence of energy impulses having a frequency, usually, varying between 16 and 5 20,000 cycles per second or those having a frequency of the order usually encountered in speech or music transmission.

My invention relates to a member or structure, as aforesaid, utilized to transmit or 10 transfer energy impulses, as aforesaid, from one region to another or from a transmitting member to a receiving member.

My invention relates to a member or structure, as aforesaid, as an arm or bar to which 15 vibratory motion is imparted by a transmitting member or system, as a phonograph record or a magnetic structure, the energy impulses actuating or controlling a suitable receiving member or system, as a diaphragm, 20 armature, or the flux in a magnetic circuit.

In accordance with my invention, a member or structure, as aforesaid, comprises an elongated, hollow circumferentially complete part or section adjacent the end thereof 25 from which impulse energy is transferred to a receiving member or system, diaphragm, or equivalent.

Further in accordance with one form of my invention, the aforesaid part or section is 30 substantially rectangular in cross-section and is shaped or folded from a suitable blank of sheet material.

Further in accordance with my invention, 35 a member or structure, as aforesaid, comprises a body portion having hinge or pivot wing structure formed integrally therewith, and more particularly, said member or structure comprises a blank of sheet material which, after being suitably shaped, has hinge 40 wings formed integrally therewith and disposed on opposite sides thereof.

Further in accordance with my invention, 45 a member or structure, as aforesaid, comprises a shaped member of sheet material terminating at one end in a web section having spaced wing hinges disposed substantially at right angles thereto and connected therewith.

Further in accordance with my invention, 50 a blank of sheet material, usually plane in

configuration, is shaped or formed to produce an elongated, hollow, circumferentially complete part or section for transmitting energy impulses.

Further in accordance with my invention, 55 one or more hinge wings is or are folded from a blank of sheet material, another portion of said blank being shaped to produce an elongated, hollow, circumferentially complete part or section, as aforesaid.

In accordance with one important phase of 60 my invention, the aforesaid member or structure is an arm or bar carrying, at one end, a stylus or needle, the other end thereof being connected to a sound-producing diaphragm. The detailed description following hereinafter refers to a construction of the character last described although it shall be understood that my invention is not to be thus limited.

My invention resides in the member or structure, article, method, and features of construction of the character hereinafter described and claimed.

For an illustration of some of the forms my 75 novel member or structure, or article may take and for an understanding of my method, reference is to be had to the accompanying drawings in which:

Figure 1 is a perspective view of a blank 80 or stamping of sheet material destined to form the body portion of a needle arm or stylus bar.

Figs. 2, 3 and 4 are perspective views illustrating steps of the folding operation.

Fig. 5 is a perspective view illustrating a 85 shaped needle arm member in substantially its complete or finished form.

Fig. 6 is a perspective view, partly broken 90 away, of a two-piece needle arm or stylus bar constructed in accordance with my invention.

Fig. 7 is a vertical sectional view, partly 95 in elevation, of the blanks illustrated in Fig. 6 after they have been assembled.

Fig. 8 is a vertical sectional view, partly 100 in elevation, of my novel needle arm or stylus bar partly broken away, and associated parts of a sound box.

Fig. 9 is a front elevational view of a part of the sound box illustrated in Fig. 8.

Fig. 10 is a transverse, horizontal sectional view taken on the line 10—10 of Fig. 9 and looking in the direction of the arrows.

Fig. 11 is a perspective view, partly broken away, of another form of a needle arm or stylus bar body portion.

Referring to Fig. 1, there is illustrated a

10 blank, stamping or part B to be comprised in the aforesaid member, structure, bar or arm and comprising, in general, a body portion or section *a* provided with slots *a*1, *a*1 extending inwardly and toward one end thereof.

15 Formed integrally with the blank B and projecting from an end thereof is an extension *b* while from the other end the spaced wing members *c*, *c* project. Ordinarily, the blank B is of plane configuration, or substantially

20 so, and is stamped from sheet material. In accordance with my invention, the configuration of blank B is subjected to a plurality of shaping operations to produce the body section proper of a needle arm or stylus bar.

25 By the first shaping operation, the wings *c*, *c* and, in accordance with the co-pending Stapler application Serial No. 312,911, filed Oct. 10, 1928, a connecting neck portion *c*1 for said wings *c*, *c* are bent or folded along a 30 line substantially as indicated by the broken line 1, Fig. 1, into a position substantially at right angles with respect to the body portion *a* to impart to the partially shaped member the configuration illustrated in Fig. 2.

35 As the next step in the shaping operation, the body portion *a* is bent or folded along lines substantially as indicated by the broken lines 2, 2, Fig. 1, to produce the flanges *d*, *d* positioned substantially at right angles with 40 respect to that part of the body section *a* remaining unaltered, said flanges *d*, *d* projecting in a direction the opposite from the direction in which the wings *c*, *c* project, Fig. 3. The partially shaped member after having been manipulated in the manner just described is illustrated in Fig. 3.

Thereafter, the body portion *a* is bent or folded along lines substantially as indicated by the broken lines 3, 3, Fig. 1 to produce the 50 upstanding, parallel walls illustrated in Fig. 4, these parallel walls having the flanges *d*, *d* extending in opposite directions therefrom and at right angles with respect thereto. The slots *a*1, *a*1 are provided to permit this folding operation.

55 As the next and final step of the body portion shaping operation, the upper portions of the aforesaid upstanding walls illustrated in Fig. 4 are bent or folded inwardly toward 60 each other along lines substantially as indicated by the broken lines 4, 4, Fig. 1, the portions designated by said broken lines, of course, having been previously folded upwardly to form the upstanding walls shown in Fig. 4. In this, the final step of the body

portion shaping operation, a structure of the character illustrated in Fig. 5 is produced wherein flanges *d*, *d* have been brought into contacting relation, or substantially so, said flanges thereafter being soldered, or otherwise suitably secured together, whereby there is produced the main body portion of the needle arm which, as clearly illustrated, comprises a tube-like member generally rectangular in cross-section.

75 As hereinafter more fully described, the aforesaid blank B, after being shaped as described, is associated, when the shaped blank constitutes, for example, a needle arm or stylus bar, directly with a sound-producing or sound box diaphragm by connection therewith of its extension *b*. The shaped member, at its other end, is adapted to receive and retain a member B1, Figs. 6 and 7, with which a talking machine needle or stylus is 80 adapted to be directly associated.

85 In the example illustrated, member B1 is generally rectangular in configuration and comprises a solid body of metal formed, preferably, by a stamping operation. The upper 90 surface thereof, as illustrated in Figs. 6 and 7, ordinarily comprises a lug or extension *g* and, as described in the aforesaid co-pending Stapler application a cross-wise slot *h*. The bottom surface thereof, as illustrated in said 95 Figs. 6 and 7, comprises a shouldered portion *i* while the rear surface thereof may be inclined as indicated at *j*. Disposed axially of the member B1 and extending a suitable distance thereinto is a passage or opening *k* for 100 the reception of a phonograph needle or stylus *l* which is retained in the position illustrated in Fig. 8 by the shank of a clamping screw *m* threaded in a passage opening into the aforesaid passage *k* at right angles with 105 respect thereto and passing through the lug *g*.

110 In the example illustrated, member B1 is assembled with or secured to the shaped member by passing the shouldered end of said member B1 into the open end of the chamber formed by the walls obtained from the body portion *a* and at the end thereof removed from the extension *b*. In so doing, as more particularly described in the aforesaid Stapler application the wings *c*, *c* and their 115 connecting neck *c*1 are temporarily bent into substantially the position indicated by the broken lines of Fig. 7 whereby the shouldered surface *i* of member B1 may be readily brought into engagement with the adjacent 120 end of the lower wall, Fig. 7, of the shaped member. Thereafter, the wings *c*, *c* and their connecting neck *c*1 may be restored to substantially the position from which they were bent, the neck *c*1 at its central portion passing 125 within the slot *h* of member B1. After being assembled in this manner, all adjacent and contacting surfaces of the two members should be soldered together.

130 A needle arm or stylus bar of the character

hereinbefore described is illustrated in Fig. 8 as forming part of a talking machine or phonograph sound box. This sound box may be of any suitable character and in Fig. 8 is illustrated as comprising a base section 10 terminating in a tubular conduit 10a adapted to be associated with the tone arm of a sound amplifying horn. A diaphragm 11 of any suitable character which, however, in the example illustrated, is of the type illustrated in the co-pending Stapler application Serial No. 311,553, filed Oct. 10, 1928, is received at its peripheral edge between washers 12, 12, a cap member 13 cooperating with a ring 14 threaded thereto to retain the diaphragm 11 in the position illustrated in Fig. 8. One side of the cap member 13 may be skeleton-like, by virtue of which one side of the diaphragm 11 is placed in direct communication, through a plurality of passages, with the surrounding atmospheric medium. On the side of the diaphragm 11 facing the conduit 10a, there may be disposed a plug or member 18 for producing properly dimensioned paths for the propagated sound waves.

In the example illustrated, the needle arm or stylus bar is secured to the diaphragm 11 only at the mid-point thereof, the member *b* constituting a tie member between the needle arm proper and the diaphragm, said member *b*, in the example shown, passing through a bushing disposed centrally of the diaphragm and being suitably secured thereto, as by a mass of wax or solder, not shown.

The wings *c* constitute the hinging or pivotal support for the needle arm or stylus bar and they may be supported in any suitable manner. To this end, in the example shown, the cap section 13 is provided with the lugs or members 15 projecting laterally therefrom, each of the aforesaid wings *c*, *c* being received between one face of a lug 15 and a plate or member 16. In the example shown, each wing *c* is provided, during the stamping operation, with a passage 2 through each of which and aligned passages in a lug 15 and member 16 extends a bolt 17 for clamping the wings and for pivotally mounting the needle arm in the position illustrated in Fig. 8. In this manner, the needle arm may be mounted for hinging or pivotal movement and, due to the fact that the wings *c*, *c* are constructed of resilient material, said needle arm is self-restoring in the sense that, of its own volition, it tends to return to an original position after being moved from such position.

Energy impulses set up by the phonograph or talking machine record are transmitted to the sound producing diaphragm by the thereto-connected needle arm or stylus bar. It is highly desirable, therefore, that the latter be so constructed as to be freely vibratable in one plane, readily restorable to an original position, and resistant to vibration

in planes other than said one plane. A needle arm constructed and mounted as hereinbefore described and illustrated is readily movable or vibratable only in the forward and reverse direction in which it moves when moving the diaphragm 11 or the central portion thereof side-wise in either direction. In other words, if the parts were positioned as illustrated in Fig. 8, the needle arm would be readily vibratable in the plane of the paper, the pivotal or hinging axis of said needle arm substantially coinciding with a line $\omega-\omega$, Fig. 10, passing through those portions of the wings *c*, *c* at the ends of the lugs 15.

At the same time, due to the construction and arrangement of parts, the needle arm is not freely vibratable or movable in a direction longitudinally thereof, nor in that direction in which it would move under the influence of friction imposed by the record which, were the parts positioned as illustrated in Fig. 8, would be substantially at right angles to the plane of the paper. The non-vibratory or non-movable features of the needle arm noted immediately above arise primarily due to the provision of a web or section *n* which remains in the original plane of blank B between the slots *a*1, *a*1 and the line 1 upon which the blank was first folded. This web or section *n* and, in accordance with the co-pending Stapler application Serial No. 312,911, neck *c*1 connect the wings *c*, *c* and constitute a structural angle section which effectively impedes and substantially prevents needle arm movement longitudinally thereof and in the direction imposed by record friction, as aforesaid. Moreover, said web or section *n* and the connecting neck *c*1, in effect, form a truss or support which braces the wings *c*, *c* and the shaped body portion *a*.

A needle arm or stylus bar constructed and mounted in accordance with my invention, besides possessing the desirable pivotal or hinging characteristic noted above, is of small weight, particularly the material from which the blank B was formed, which may be elastic or resilient in character, as steel or bronze having a thickness of the order of 0.008 of an inch, more or less. Due to this feature, the moment of inertia about the axis $\omega-\omega$ is small and, as a result, the quality of sound production is improved.

A feature of my invention of distinct importance involves the provision of a needle arm, or equivalent, comprising an elongated hollow, circumferentially complete part or section, such as the member formed from the blank B. Except for the part thereof occupied by the member B1, said member formed from the blank B, entirely hollow, extends to substantially the region where engagement is effected with the diaphragm. Due to its shape, even though hollow, the member formed from the blank B is suf-

ficiently strong to be substantially or largely free of any deformation or flexing by reason of motion imparted thereto by the talking machine needle or stylus. Moreover, since said member formed from the blank B is circumferentially complete, free or unsupported walls, such as exist, for example, with or in a channel section, are absent and, accordingly, the formation of local vibrations in the needle arm is impeded or prevented, this, of course, improving the quality of sound production.

Although the member formed from the blank B has been illustrated and described as formed from a member which is brought to a configuration generally rectangular in cross-section, it shall be understood that my invention is not to be thus limited. Thus, for example, in lieu of a shaped member, or one that is formed from a stamping, there may be utilized an elongated, hollow, circumferentially complete member formed in any suitable manner and having any suitable cross-sectional form. In any event, it is desirable that the member formed from the blank B, or equivalent, as just described, be tapered in a direction leading from the needle arm hinging support toward the center of the diaphragm. This construction decreases the needle arm weight without sacrifice of strength.

Although a feature of my invention involves the provision, on each side of the needle arm, or equivalent, of hinge wings, such as the wings c, c formed integrally with the body portion a, it shall be understood that my invention is not be thus limited, for under some circumstances, it may be desirable to utilize some other type of pivoting or hinging arrangement. In such case, however, it is desirable to dispose a hollow, circumferentially complete member or structure between the needle arm pivot and diaphragm center, the integral hinge wings, or wings of any character whatsoever being omitted. However, it may be desirable to utilize hinge wings with a construction of the character last described, the wings, however, not being formed integrally with the hollow, circumferentially complete member.

It is highly desirable that the connecting tie member b be formed integrally with the needle arm proper and this may readily be accomplished by forming the part b by the same die structure that forms the blank B. In accordance with my invention and in contra-distinction to prior art arrangements, the diaphragm is connected by a single member b, and still further distinguishing from prior art arrangements, said member b is stiff and rigid in a direction longitudinally thereof and freely flexible or pliable in that plane at right angles to the diaphragm and in which the longitudinal axis of the needle arm is included, Fig. 8. Moreover, since the material forming the blank B is very thin, it fol-

lows that the mass of the tie member b is kept small, this being highly desirable.

The tie member b may lead direct to the diaphragm or, preferably and as illustrated, the connection may be circuitous and comprise a U-shaped bend b1, or equivalent, by virtue of which the flexibility of the tie connection is improved. It should also be noted that there is a portion b2 of the tie member b beyond the hollow, circumferentially complete body portion of the member formed from blank B. This portion b2 of the tie member is substantially in alinement with one wall of said structure and, during a period of sound production, flexing or giving action in the needle arm proper largely occurs in portions b1 and b2.

To further enhance the freedom with which the needle arm pivotally moves in the desired direction, as aforesaid, material may be removed from the axis x-x. In the example shown, this result is attained by forming, during the stamping operation, a plurality of openings or holes c3 in those regions of the wings c, c destined to fall within the aforesaid axis x-x.

It will be observed that the hinge wings c, c which are formed integrally with the member formed from the blank B are disposed on opposite sides thereof and equal distances from the diaphragm 11. Preferably, said wings c, c are placed in a single plane disposed substantially at right angles to the plane of diaphragm 11 which, in the example illustrated, is a plane passing between the rings 12, 12. This feature is of distinct importance since, with a construction of the character illustrated, the diaphragm velocity, i. e. side-wise vibration, is largely or substantially independent of deflection or bending of the needle arm hinge wings, a condition which is not satisfied when said hinge wings are disposed in a plane substantially parallel with the plane of the diaphragm.

Referring to Fig. 11, there is illustrated a shaped part or element Y which corresponds with the shaped part or element shown in Figs. 5 and 6 save that the body portion is circumferentially incomplete rather than complete. A needle arm, or equivalent, of the character illustrated in Fig. 11 may be formed from a blank of the type shown in Fig. 1 if the material on each side thereof outwardly of the lines 4, 4 is omitted.

Although the formation of the shaped member has been described as following a particular sequence of steps, it shall be understood that any desired sequence of steps may be followed and that, if desirable and advisable, the completed blank may be produced by performing all of the folding operations substantially simultaneously. Moreover, forming dies, not shown, usually are necessary to bring the blank to its proper configuration.

Although the aforesaid members, struc-

tures, bars or arms have been illustrated and described as operated by a phonograph or talking machine record, it shall be understood that my invention is not to be thus limited.

5 Thus, for example, said members, structures, bars or arms may be magnetically actuated, the needle or stylus, in such case, being omitted.

Although the hereinbefore described members, structures, bars or arms have been specifically referred to for diaphragm-actuating purposes, it shall be distinctly understood that my invention is not to be limited to such an arrangement. Thus, for example, said 10 members, structures, bars or arms, actuated or vibrated by a stylus or needle, or otherwise as desirable, may be utilized to transfer impulse energy to the vibrating element or to serve as the vibrating element of any device 15 for which they are adapted, particularly devices which vibrate in accordance with sound.

What I claim is:

1. A vibratable member comprising a structure shaped from sheet material and terminating at one end in a web section, and spaced 20 wing hinges disposed substantially at right angles to said web section and connected thereto.

2. A vibratable member comprising a body 25 portion including a web section, and spaced wing hinges disposed substantially at right angles to said web section and connected thereto.

3. A vibratable member comprising a 35 structure shaped from sheet material and having a hollow, circumferentially complete portion substantially rectangular in cross-section, one wall of said hollow portion terminating in a web section of greater width 40 than said wall, and spaced wing hinges disposed substantially at right angles to said web section and connected thereto.

4. A device of the class described comprising a hollow circumferentially complete 45 member having flat sides, one of said sides being extended beyond said circumferentially complete member and being widened to form a web, said web having portions extending at right angles thereto to form supporting 50 hinges for said device.

5. In combination with a member to be vibrated, a vibratable member comprising a hollow circumferentially complete portion having a section extending beyond the end of 55 said member to form a narrow flexible strip, said strip being adapted to be secured to a member to be vibrated and having a U-shaped bend therein.

6. A vibratable member comprising a hollow circumferentially complete portion having a section extending beyond one end thereof to form a narrow flexible strip, said strip being adapted to be secured to a member to be vibrated and having a U-shaped bend 65 therein, and laterally extending wings se-

cured to said circumferentially complete portion for supporting said device.

7. A vibratory device of the class described, comprising a hollow circumferentially complete member having flat sides, one of said sides being extended beyond one end of said member to form a narrow flexible strip, said strip being adapted to be secured to a member to be vibrated and having a U-shaped bend therein, and one of said sides being extended beyond the other end of said circumferentially complete member and terminating in a web section having laterally extending supporting wings. 70

8. A vibratable member comprising a hollow circumferentially complete portion having flat sides, one of said sides being extended beyond one end of said portion to form a narrow flexible strip, said strip being adapted to be secured to a device to be vibrated and having a U-shaped bend therein, and one of said sides being extended beyond the other end of said circumferentially complete portion and widened to form a web, said web having portions extending at right angles thereto to form supporting means for said vibratable member. 75

In testimony whereof I have signed this specification this 8th day of October, 1928.

CERTIFICATE OF CORRECTION.

Patent No. 1,813,579.

Granted July 7, 1931, to

RUDOLPH F. MALLINA.

It is hereby certified that error appears in the printed specification of the above numbered patent requiring correction as follows: Page 1, line 79, for the word "drawings" read drawing; page 5, lines 51 and 52, claim 5, strike out "In combination with a member to be vibrated,"; line 52, the article "a" first occurrence should be capitalized; and that the said Letters Patent should be read with these corrections therein that the same may conform to the record of the case in the Patent Office.

Signed and sealed this 22nd day of September, A. D. 1931.

(Seal)

M. J. Moore,
Acting Commissioner of Patents.
